2,816,334

AUTOMATIC LADLING CONTROL FOR METAL MELTING FURNACE

Elmer W. Edstrand, Berkeley, Ill., assignor to Lindberg Engineering Company, Chicago, Ill., a corporation of Illinois

Application September 24, 1956, Serial No. 611,419

12 Claims. (Cl. 22—79)

This invention relates generally to metal melting furnaces and more particularly to an automatic ladling control for metal melting furnaces.

Metal melting furnaces are known in the prior art wherein a charge of cold metal is heated to a molten state or is held in a molten state by electric induction, fuel combustion and the like and the molten metal resulting from the heating is removed from the furnace by means of a pump associated with the furnace. Advantageously, the pump may be of the type which is seated over the open upper part of the furnace and which causes the molten metal to be discharged through a suitable discharge channel connected to the pump by applying gas pressure to the surface of the molten metal.

Inasmuch as the discharge channel generally extends a substantial amount into the molten metal within the furnace it has been found that the amount of molten metal discharged by the operation of the pump for a set time varies in accordance with the level of the molten metal within the furnace. Manifestly this condition is a wholly unsatisfactory one as it is desirable in a large number of applications that a uniform amount of molten metal be discharged for every operation of the pump.

Accordingly, it is a general object of this invention to provide improved means for controlling the discharge of molten metal from a furnace.

More specifically it is an object of this invention to provide an improved control circuit which compensates for variations in the level of molten metal within a furnace to discharge a predetermined amount therefrom.

It is another object of this invention to provide an improved ladling control for a metal melting furnace which automatically enables the discharge of a uniform amount of metal therefrom regardless of the level of the metal within the furnace.

It is a further object of this invention to provide electronic means responsive to the quantity of molten metal in a metal melting furnace for controlling the amount of molten metal discharged therefrom.

It is a still further object of this invention to provide an improved control circuit for automatically determining the period of operation of a discharge pump associated with the furnace.

It is a still further object of this invention to provide such an improved automatic ladling control for metal melting furnaces which is characterized by its compactness, efficiency and sensitivity.

In accordance with a specific illustrative embodiment of this invention the automatic ladling control comprises a pump operating valve adapted to permit the crucible of a metal melting furnace to be pressurized for causing the discharge of molten metal therefrom. The period of time during which the pump operating valve is energized is controlled by a novel electronic circuit having a discharge device which is maintained nonconductive for the desired length of time after the discharge operation is initiated.

The discharge device is held in normally nonconducting condition by a bias potential applied thereto. The control further comprises a float adapted to be placed in the molten metal within the furnace crucible such that its level varies in accordance with the level of the molten metal. The float is connected to a potentiometer wiper which provides an output voltage that varies in accordance with the position of the float. The potentiometer output voltage controls the magnitude of the bias potential applied to the discharge device, which potential is removed when the pump operation is initiated. Thus, the position of the float, i. e., the level of the molten metal in the furnace crucible, determines the period of time after removal of the bias voltage, before the discharge device becomes conductive and stops the pump.

Therefore, it will be understood that for relatively high levels of molten metal within the furnace crucible the bias potential on the discharge device will be such as to cause it to become conductive a relatively short period of time after the pump is started and conversely for low levels of molten metal within the furnace crucible the bias potential on the discharge device will be such as to cause it to become conductive a relatively long period of time after the pump is started. Since the energization of the pump operating valve for discharging the molten metal from the crucible is dependent upon the interval between pump initiation and discharge device conducting automatic compensation for variations in the level of the molten metal within the crucible is provided to insure that an equal amount of molten metal is discharged for each operation of the pump.

The above and other features of novelty which characterize the invention are pointed out with particularity in the claims appended to and forming a part of this specification. For a better understanding of this invention, however, its advantages and specific objects attained by its use reference is had to the accompanying drawing and descriptive material in which is shown and described an illustrative embodiment of the invention.

In the drawing:

Figure 1 shows a metal melting furnace of a type embodying the present invention; and

Figure 2 is a schematic diagram of the electronic control circuitry embodying the invention.

Referring now to the drawing and more particularly to Figure 1 there is shown a dual chamber type induction furnace with which the invention advantageously may be used. The furnace as shown comprises a main body 10 which may be formed of ceramic or refractory material to withstand the heat of the molten metal without damage. In the dual chamber induction furnace shown the body is formed with a melting chamber 12 which may be relatively large and with a pouring or ladling chamber 14 spaced horizontally from chamber 12 and preferably smaller than the latter. Both chambers are adapted to contain molten metal 16 and may be connected by spaced channels 18 formed in the body 10 and lying below the normal level of molten metal in the chambers through which the metal can flow from the melting chamber to the ladling chamber.

Metal in the chambers is heated by means of a transformer primary loop, indicated generally at 20, which is positioned between the melting and ladling chambers and is magnetically linked with channels 18. As is well known in the art the primary loop 20 is energized to produce a flow of secondary heating current for melting the metal in the furnace.

A pump assembly indicated generally as 22 is positioned in operative relation with the molten metal 16 in ladling crucible 14. Pump 22 comprises a pump chamber 24, which advantageously is formed of refractory material.

Pump chamber 24 is hollow and has an elongated body extending substantially below the level of molten metal 16. An opening 26 is provided at the bottom of pump chamber 24 for enabling the molten metal in chamber 14 to seek its level within pump chamber 24. A discharge channel 28 is connected to pump chamber 24 and is adapted to communicate with the molten metal within the pump chamber by means of an opening provided therebetween at the lower end of the pump chamber. Discharge channel 28 extends through an opening in a side wall of the furnace body 10 where it advantageously may be connected to suitable molten metal receiving apparatus.

Pump control assembly 22 is seated on a cover plate 30 positioned over the chamber 14 such that when the pump chamber is pressurized by air supplied thereto from a pump operating valve the molten metal within the pump chamber 24 is forced up through the discharge channel 28 and out of the furnace. The inlet opening 26 is made small to limit backflow of metal to the chamber 14 during this operation.

It readily will be appreciated that when the pump chamber is pressurized for set periods of time the amount of molten metal discharged from the furnace varies in accordance with the level of the molten metal in the furnace. As it normally is desirable to discharge equal amounts of molten metal from the furnace for each operation of the pump, an electronic control circuit is provided with the furnace to automatically compensate for changes in level to thereby equalize the amount of molten metal discharged from the furnace.

In accordance with an aspect of this invention a float 32, which advantageously may be formed of a ceramic material, is placed in supported position within pump chamber 24 so as to float on the molten metal 16 therein. A shaft 34 is connected to the float 32 and is adapted to follow the float in accordance with changes in the level of molten metal in the furnace. A portion of the control circuit is provided within a housing 36 positioned above the float and is adapted to cooperate with a suitable electronic timing circuit, as described below, to vary the operating time of the pump in accordance with the level of molten metal 16 as indicated by changes in the position of shaft 34. As shown in Figure 2, and as described below in connection therewith, shaft 34 is connected to the wiper 90 of a potentiometer 86 positioned within housing 36 to the end that variations in the level of the molten metal within the furnace are communicated by the follower action of the float 32 and shaft 34 to wiper 90 to thereby cause corresponding changes in the position of the wiper.

A preferred embodiment of the control circuit is shown in Figure 2 of the drawing. The control circuit comprises a transformer 40 having a primary winding 41 which is connected through fuse 39 across a pair of line conductors 42 and 43, which, in turn, are connected to a source of A. C. supply voltage (not shown). One secondary winding 44 of transformer 40 is connected to filaments 45 and 46 of a pair of discharge devices 47 and 48, respectively, to supply heater voltage thereto. Another secondary winding 49 of transformer 40 is connected at one end thereof to the anode 50 of rectifier tube 47 and at the other end thereof through a capacitor 51 to cathode 52 of rectifier tube 47.

Cathode 52 of rectifier tube 47 is connected to a range and calibration network comprising a calibration potentiometer 53 connected in series with a pair of fixed resistors 54 and 55 and a calibration potentiometer 56. The contacts of a range switch 57 are connected across potentiometer 53 and resistor 54.

Discharge device 48 has its anode 60 connected through the windings of relay 61 to line conductor 43. Control grid 62 of discharge device 48 is connected through a resistor 63 to potentiometer 56. Screen grid 64 and cathode 65 of discharge device 48 are connected through fuse 39 to line conductor 42. Cathode 65 also is connected

to one terminal of condenser 66, the other terminal of which is connected to control grid 62.

Condenser 67 is connected between potentiometer 56 and winding 49 of transformer 40. Resistor 68 is connected in series with contacts 69 and 70 of relay 71 across condenser 67. Contacts 72 and 73 of relay 71 are connected between cathode 65 of discharge device 48 and one terminal of a bleeder potentiometer 74.

Potentiometer 74 is connected across the output of a rectifier which comprises a transformer 75 having a primary winding 76 connected across line conductors 42 and 43, and a secondary winding 77 connected to a rectifier bridge network comprising rectifiers 78, 79, 80 and 81. The output of the rectifier bridge network comprises a filter including condensers 82 and 83 and a resistance 84 connected therebetween. Bleeder potentiometer 74 is connected across condenser 83. Wiper 85 of potentiometer 74 is connected to a terminal of potentiometer 86, the other terminal of which is connected to relay contact 73. One terminal of potentiometer 87 is connected to secondary winding 49 of transformer 40 and the other terminal is connected through resistance 88 to cathode 52 of rectifier 47. Wiper 90 of potentiometer 86 and wiper 91 of potentiometer 87 are connected electrically and the former is mechanically coupled by shaft 34 to float 32. Thus wiper 90 is adapted to be adjusted in accordance with the position of the float as determined by the level of the molten metal 16 within ladling chamber 14.

Contacts 92 and 93 of initiating switch 94 are connected between line conductor 43 and relay 71. Contact 92 of switch 94 also is connected to armature contact 103 of switch 102 of relay 71. Contact 104 of switch 102 is connected to armature contact 95 of relay 61 and to a terminal of relay 101. The other terminal of relay 101 is connected to line conductor 42. Contact 96 of relay 61 is connected to a terminal of ladling relay 97. The other terminal of ladling relay 97 is connected to line conductor 42. Pump operating valve 98 is connected at its terminals to line conductor 42 and at its other terminal to armature contact 99 of ladling relay 97. Contact 100 of ladling relay 97 is connected to line conductor 43.

In the operation of the control circuit, discharge device 48 normally is biased to its nonconducting condition by bias potentials applied between its control grid 62 and its cathode 65 from two separate voltage sources. One bias potential is derived from rectifier tube 47 and is applied through the circuit comprising potentiometer 53, resistances 54 and 55, potentiometer 56 and resistance 63 to the control grid 62 of discharge device 48. A second bias potential is derived from the rectifier bridge network comprising the rectifiers 78, 79, 80 and 81, its filter network and potentiometer 74 and is applied through potentiometer 86 and its wiper 90 to wiper 91 of potentiometer 87.

Wiper 90 of potentiometer 86 is mechanically coupled to ceramic float 32 in the pump chamber 24. Thus, as the level of molten metal 16 in chamber 24 varies, the voltage at wiper 90 of potentiometer 86 varies accordingly and is added to the voltage at potentiometer 87. The resultant bias voltage on discharge device 48 is the sum of these two bias potentials and charges capacitances 66 and 59 to apply this voltage at cathode 65 of discharge device 48 and maintain the latter in a nonconducting condition.

When it is desired to ladle an amount of molten metal 16 from the furnace through discharge channel 28, contacts 92 and 93 of initiating switch 94 are closed. This causes relay 71 to be energized, since it has been placed directly across line conductors 42 and 43, and results in the opening of its normally closed contacts 69 and 70 and the closing of its normally open contacts 103 and 104.

The energization of relay 71 and the subsequent opening of its normally closed contacts 69 and 70 initiates the timing cycle of the circuit. At this time, however, ladling relay 97 also is energized through a circuit including line

conductor 43, initiating switch contacts 92 and 93, closed contacts 103 and 104 of relay 71, normally closed contacts 95 and 96 of relay 61, relay 97 and line conductor 42. The energization of relay 97 closes its normally open contacts 99 and 100 to energize the pump operating valve 98 and thereby initiate the pumping of molten metal from the furnace. Advantageously, pump valve 98 may be of the air or gas solenoid type whereby energization of the valve opens a line to pump chamber 24 to presurize the latter and force molten metal 16 through discharge channel 28.

The opening of contacts 72 and 73 as a result of the energization of relay 101 and the opening of contacts 69 and 70 as a result of the energization of relay 71 removes the bias potential supplied from the rectifier bridge from the storage capacitors 66 and 59. Capacitors 66 and 59, which previously had been charged to a voltage representing the sum of the two bias potentials maintains the bias potential on cathode 65 of discharge device 48 and holds the latter in a nonconductive state. With contacts 69 and 70 of relay 71 open, capacitor 67 begins to charge to the value determined by storage capacitor 59. When capacitor 67 has charged to the predetermined bias voltage of capacitors 59 and 66, discharge device 48 starts to conduct and relay 61 in its anode circuit is energized. The energization of relay 61 causes its normally closed contacts 95 and 96 to open and thereby open the power circuit to ladling relay 97. The resultant de-energization of relay 97 reopens its contacts 99 and 100 and consequently de-energizes the pump valve 98 to terminate the pumping action in the crucible.

It will be understood by those skilled in the art that the period of time defined by the addition of the second bias potential to discharge device 48 and the additional subsequent conduction of the latter is determined by the amplitude of the second bias potential. Thus, for a relatively large second bias potential, the timing cycle will be considerably lengthened, for a relatively small second bias potential, the timing cycle will be correspondingly shorter. The reference time is set by suitable adjustment of potentiometer 87 in the control circuit and this time is varied in accordance with the metal level by potentiometer 86 coupled to float 32. Thus the amplitude of this second bias potential is determined by the position of float 32 in pump chamber 24 and the length of the timing cycle is varied directly by the level of the molten metal in the furnace. When this level is a relatively high one the second bias potential added to the first bias potential is small and the increase in the timing cycle is relatively short. When the level of the molten metal is low the second bias potential is correspondingly greater and the increase in the timing cycle is long. In this manner variations in the level of the molten metal 16 in the furnace are compensated for and a uniform amount of molten metal is discharged from the furnace for every ladling operation regardless of the level of molten metal within the furnace.

It will be appreciated that the range of the automatic ladling circuit may be changed to conform with the size of the furnace used by changing the position of switch 57 in the output of rectifier tube 47 and by suitable adjustment of potentiometer 87. Potentiometers 53 and 56 are calibration potentiometers and once set are never changed in position. Additionally, the circuit may be adjusted and balanced by properly positioning wipers 85 and 91 of potentiometers 74 and 87 respectively.

It will be understood by those skilled in the art that modifications may be made in the construction and arrangement of the parts of the above described automatic ladling control means without departing from the real purpose and spirit of the invention and that it is intended to cover by the appended claims any modified forms of structures, circuits or use of equivalents which reasonably may be included within their scope.

What is claimed is:

1. A metal melting furnace having means for automatically ladling a predetermined amount of molten metal comprising a chamber to hold molten metal, a discharge channel disposed in said chamber, pump means for causing the molten metal to be discharged through said discharge channel, a float positioned in said chamber such that its position is varied in accordance with the level of the molten metal therein and actuating means operatively connected to said float and responsive to the level of the molten metal as indicated by the position of said float for causing said pump means to be operated a period of time sufficient to discharge a predetermined amount of molten metal from the chamber regardless of the level of the molten metal therein.
2. A metal melting furnace comprising a chamber to hold molten metal, a discharge channel disposed in said chamber, pump means for causing the molten metal to be discharged through said discharge channel, switch means for initiating operation of said pump means, and a circuit including a timer responsive to the level of the molten metal in the chamber for automatically terminating the operation of said pump means after a period of time determined by the setting of the timer and the level of the molten metal.
3. A metal melting furnace in accordance with claim 2 wherein said circuit includes storage means for storing a bias potential having an amplitude varying with the level of the molten metal in said chamber.
4. A metal melting furnace in accordance with claim 3 further comprising a float adapted to be placed in said molten metal whereby its position is varied in accordance with the level of the molten metal, a source of potential having an output controlled by the position of said float, and means for applying said output to said storage means.
5. A metal melting furnace having means for automatically ladling a predetermined amount of molten metal comprising a chamber to hold molten metal, a discharge channel disposed in said chamber, pump means including a solenoid valve adapted to render said pump means operative upon operation of said solenoid valve for causing the molten metal to be discharged through said discharge channel, actuating means controlled by the level of the molten metal for operating said solenoid valve for a period of time sufficient to discharge a predetermined amount of molten metal from the chamber regardless of the level of the molten metal therein.
6. An automatic ladling control circuit for a metal melting furnace of the type having pump means associated with a chamber for causing the discharge of molten metal therefrom comprising a first source of bias voltage, a second source of bias voltage, a discharge device including an anode, a cathode and a control grid, means for applying bias voltages from the first and second sources to the cathode and control grid of said discharge device to maintain the latter in a nonconducting condition, said means including storage capacitance means capable of being charged to said bias voltages and maintaining said bias voltages upon removal from said bias voltage sources, switch means operative to start the pump means and to remove the sources of bias voltage from said cathode and control grid whereby said storage capacitance means maintain predetermined cathode and grid bias voltages and allow said discharge device to remain nonconductive until a desired time cycle has been completed, switch means responsive to the conduction of said discharge device to stop the operation of said pump means and control means operative to vary the bias voltage from said second source in accordance with the level of the molten metal in said chamber whereby the period of operation of said pump means is varied by the level of the molten metal in the chamber.
7. An automatic ladling control in accordance with claim 6 wherein said control means comprises a float

adapted to be supported by said molten metal at substantially the level of the latter within the chamber.

8. An automatic ladling control in accordance with claim 7 wherein said second source of bias potential comprises a rectifier circuit having a D. C. voltage output, and further comprising a resistance connected to said rectifier circuit, a wiper adjustably associated with said resistance, and shaft means mechanically coupling said float to said wiper whereby the voltage at said wiper is varied in accordance with the position of said float.

9. Melting furnace apparatus comprising a chamber to hold molten metal, pump means operatively associated with said chamber for causing molten metal to be discharged therefrom and circuit means for controlling the amount of molten material discharged, said circuit means comprising a discharge device, means for maintaining said discharge device in a nonconducting condition including a source of bias potential, storage capacitance means connected to said discharge device and adapted to be charged to said bias potential, means operative to initiate operation of said pump means and to remove said bias potential source from said discharge device whereby said storage capacitance means maintains a bias potential on the discharge device until the latter is triggered into conduction, and means responsive to the conduction of said discharge device when said bias applied thereto attains a value more

20 positive than the cut-off potential of the discharge device for terminating the operation of said pump means.

10. Melting furnace apparatus in accordance with claim 9 further comprising means responsive to the level 5 of the molten material in said chamber for varying said bias potential whereby the period of operation of said pump means is varied by the level of said molten material.

11. Melting furnace apparatus in accordance with claim 10 further comprising means for terminating the conduction of said discharge device upon termination of the operation of said pump means whereby said circuit means is placed in condition for a further discharge of the molten metal from the crucible.

12. Melting furnace apparatus in accordance with claim 15 11 wherein circuit means further comprises adjustable means for selectively varying the range of operation of said circuit means.
